BENJAMIN J. NASIEF AND FARNUM F. DORSEY, OF ROCHESTER, NEW YORK, ASSIGNEES, BY DIRECT AND MESNE ASSIGNMENTS, TO ANSCO COMPANY, OF BINGHAMTON, NEW YORK, A CORPORATION.

ROLL-FILM-DEVELOPING APPARATUS.

1,156,922.

Specification of Letters Patent.

Patented Oct. 19, 1915.

Application filed April 28, 1915. Serial No. 24,589.

To all whom it may concern:

Be it known that we, BENJAMIN J. NASIEF and FARNUM F. DORSEY, being, respectively, a subject of the Sultan of Turkey and a citizen of the United States, and residents of Rochester, in the county of Monroe and State of New York, have invented certain new and useful Improvements in Roll-Film-Developing Apparatus, of which the following is a specification.

This invention relates to apparatus in which, as a preparation for the development of a roll-film, the film is rewound from the film-reel upon a support of some character for retaining the film in a suitable position or condition for subjection to the developing-solution. Such a support, usually comprises a flexible apron for holding the film with sufficient space between its layers or turns for the admission of the developing solution, but the particular character of the support in question is not essential to the present invention.

The object of the invention is to permit, as an incident to the rewinding operation, the separation of the paper backing-strip from the film-strip, so that during the developing operation the backing strip shall not be in contact with the film. It has been found that when the backing-strip is in contact with the film the dye, by which the backing-strip is colored, becomes more or less dissolved and tends to stain the film, and as this dye is of a non-actinic color, the stains so produced cause blemishes in the prints made from such film.

To the foregoing end the present invention comprises means for receiving the backing-strip and for retaining it separate from the film-strip during the rewinding of the latter. As incidental to the operation of such means, the invention also comprises, in its preferred form, a modification in the film-package, itself, which facilitates the proper preparation of the backing-strip for the action upon it of the means in question. To this end the invention comprises a film-package or reel in which the usual backing-strip, extending beyond the advance end of the film-strip so as to constitute a leader for the latter, is provided with a line of demarcation, preferably in the form of perforations or a weakened line of some character,

located adjacent the advance-end of the film-strip, so that after the film has been secured to the backing-strip in the usual manner, as a preliminary to the rewinding operation, the backing-strip may be conveniently severed at the line in question, so that after that portion of the backing-strip which constitutes the leader has been rewound in advance of the film, the main portion of the backing-strip, which is contiguous with the film in the film-roll, may be deflected and guided away from the film during the rewinding of the latter.

In the accompanying drawings:—Figure 1 is a longitudinal vertical section of rewinding-apparatus embodying the present invention; Fig. 2 is a plan-view of the same; and Fig. 3 is a perspective view of a film-roll, partly unwound, and constructed in accordance with the present invention.

The invention is illustrated as embodied in a rewinding-apparatus of which the general form and construction are well known. Within a light-tight casing 7 two spindles 5 and 6 are journaled, these spindles being provided with cranks 8 and 9 by which they may be turned. The spindle 5 is used to support the usual flexible developing-apron 10, while the spindle 6 is employed to wind the apron and the film-strip together, this spindle being provided with light-tight metal flanges 14 at its ends. The ordinary film-reel 13 is supported in the casing by adjustable bearing-members 11 and 12, and after the reel has been so mounted, the outer end of the paper backing-strip is attached to the spindle 6, together with the end of the apron 10, and this spindle is then rotated to perform the rewinding operation. As so far described, the rewinding apparatus is of a well-known form.

In a film-package as usually constructed a continuous opaque backing-strip 15 of paper is wound with the film-strip 16, as shown particularly in Fig. 3, and extends beyond the film-strip at both ends, so as to provide leaders for use both in the camera and in the developing-apparatus. The film-strip is also provided with a transverse fastening-strip of gummed paper 17, which adheres to the advance-end of the film-strip but is left loose from the backing-strip until the film is to be rewound. Prior to the

rewinding operation this fastening-strip 17 is to be moistened and gummed down to the backing-strip, so that usually the film-strip and the backing-strip are rewound together.

In accordance with the present invention the backing-strip is provided with a transverse line of demarcation 18, located approximately at the position of the advance-end of the film-strip as fastened to the backing-strip. This line is preferably produced by perforating or otherwise weakening the backing-strip, though any mark plainly visible to the user may be used for the same purpose. Before sticking the connecting-strip to the backing strip the user severs the leading portion of the backing-strip from the body of the strip, on the line 18, by either tearing or cutting it, and then sticks the connecting-strip to the leading portion, and, finally, rewinds the backing-strip on the reel for one or more turns. The reel is then placed in the rewinding-apparatus in the usual manner, and the backing-strip connected with the rewinding-spindle 6. When this spindle is turned the part of the backing-strip in advance of the line of severance, which part is designated in the drawings by the reference-number 19, constitutes a leader in the usual manner, but as soon as this leader has been sufficiently unwound from the reel to release the part of the backing-strip in the rear of the line of severance, the advance-end of this part, being loose, can be separated from the film and guided to a position away from the rewinding spindle. This operation is facilitated by the tendency of the paper to separate itself from the film-strip, owing to its inherent elasticity. To insure such separation of the paper from the film, and to provide a separate receptacle for the paper, a guide 20 is employed, in the form of a metal plate mounted beneath the film-reel on a pivot-rod 21, about which it may swing upwardly, and a spring 22, coöperating with the guide, presses it lightly against the surface of the film on the reel. Accordingly, the paper passes in front of the guide 20, as shown in Fig. 1, and is thus separated from the film. As the rewinding operation is continued the paper tends to curl up in the space below the reel and the guide 20, and to insure that it shall not be accidentally drawn into engagement with the apron and thus wound up therewith, a second guide 23 is employed, in the form of a resilient sheet-metal plate which is fixed to the bottom of the casing and extends upwardly into a position adjacent the stretch of film between the film-reel and the rewinding-spindle. As the diameter of the roll formed by the paper and the film increases, this guide 23 yields so as not to interfere with the rewinding operation.

The guides 20 and 23, together with the adjacent parts of the casing, constitute a receptacle into which the backing-strip is guided, and in which it is retained until the film has been entirely rewound. After 70 the completion of this operation, however, since the backing-strip is cemented to the rear end of the film-strip, the continued rotation of the spindle causes it to be first doubled back at this end, and then drawn from the receptacle in question to the rewinding-spindle, together with the rearmost portion of the backing-strip which constitutes the leader at the rear end of the film-strip, and the two parts of the backing-strip are then wound either with or upon the apron, so that at the completion of the rewinding operation no further operation on the part of the user is necessary. Since the backing-strip as so wound is not in contact with any part of the film, except at the extreme ends of the latter, no staining of the film will occur, but if it be considered desirable the apron may be carefully unwound enough to permit the paper to be detached from the rear end of the film-strip without exposing the latter, so that, except for the forward portion or leader 19 of the backing-strip, no part of the backing-strip necessarily enters the developing solution.

While the guide-plates above described constitute simple and effective means for controlling the movement of the backing-strip during the rewinding operation, the invention is not limited to embodiment in 100 this specific form, but may be embodied in various other forms within the nature of the invention as it is defined in the following claims.

We claim:—

1. In roll-film developing apparatus, the combination, with a reel-support and a rewinding device, of means for engaging the end of the backing-strip as the film is unwound from the reel and automatically separating it from the film while the film is rewound.

2. In roll-film developing apparatus, the combination, with a reel-support and a rewinding device, of a guide located adjacent the film-reel and adapted to enter between the roll and the end of the backing-strip so as to separate the latter automatically from the film as the film is unwound from the reel.

3. In roll-film developing apparatus, the combination, with a reel-support and a rewinding device, of a guide located adjacent the rewinding device and adapted to deflect the backing-strip from the film during the 125 rewinding operation.

4. In roll-film developing apparatus, the combination, with a reel-support and a rewinding device, of means located adjacent the reel-support and the rewinding device 130

and constituting a receptacle to receive the backing-strip and retain it while the film is rewound.

5. The combination, with a film-reel, a reel-support, and a rewinding device, of a film-strip; a backing-strip extending only to the advance-end of the film-strip; a

leader extending from the film-strip and adapted for attachment to the rewinding device; and means for receiving the backing- 10 strip and for retaining it separate from the film-strip during the rewinding of the latter.
